ATTORNEY

UNITED STATES PATENT OFFICE.

CHARLEY GRANT WARD, OF JEFFERSONVILLE, INDIANA.

FILE-CABINET.

No. 900,242.

Specification of Letters Patent.

Patented Oct. 6, 1908.

Application filed November 1, 1907. Serial No. 400,163.

To all whom it may concern:

Be it known that I, CHARLEY GRANT WARD, a citizen of the United States, residing at Jeffersonville, in the county of Clark and State of Indiana, have invented a new and useful File-Cabinet, of which the following is a specification.

The object of the invention is the provision of a file cabinet particularly adapted for use with a filing system which will be hereinafter described.

Figure 1 is a perspective view of the cabinet closed; Fig. 2, a perspective view of the cabinet with the front door let down to form a table; Fig. 3, a perspective view showing the cabinet with the front door down and the inner doors open; Fig. 4, a perspective detail view, showing the compartments; Fig. 5, a plan view of the salesman's order book; Fig. 6, a rear view of a portion of a book of duplicate orders assembled; Fig. 7, a transverse sectional view of a book of duplicate orders assembled; Fig. 8, a view showing the arrangement of the register of salesmen; Fig. 9, a view showing the arrangement of the ledger index; and, Fig. 10, a view showing the arrangement of the ledger.

Similar reference numerals refer to similar parts throughout the several views of the drawings.

A book or pad 1, of order blanks (Fig. 5) is provided, consisting of printed pages numbered consecutively with numerals preferably printed in red in order that they may not be obliterated by writing over them with a pencil. The lines upon which the names of the articles ordered are to be written may be numbered as shown. Beneath each order blank is provided a blank leaf 3, upon which a carbon or duplicate copy of the written order is made. A carbon sheet 4 is provided to be placed between the order blank and the blank leaf. This form of duplicate order book I do not claim as my invention, for it is already on the market. An order book, such as described, is given to each salesman at the beginning of the day. The order blanks and duplicate pages are perforated in the usual manner, as shown at 5, in order that they may be easily removed from the stub 6, where they are bound together.

When the order books are given to the salesmen, the ordinal number, shown at 2, upon the topmost blank is recorded opposite the salesman's number under the proper date

in a register of salesmen 7 (Fig. 8). The page shown in Fig. 8 shows that all the salesmen started with a new book on January 1st, and consequently the order blanks are all No. 1. On January 1st, salesman No. 1 may have written fourteen orders, and hence the topmost blank on his order book, on January 2nd, will be No. 15. The salesman's register is kept in order to determine how many order blanks each salesman has used during the day in order that they may all be accounted for at the end of the day.

At the end of the day each salesman passes in his pad of duplicate orders to the proprietor or the bookkeeper. If the proprietor keeps the books, which he may easily do with my improved system, he takes the pads consecutively, looks through each pad to ascertain if the duplicates are consecutive and none are missing, removes the duplicates from the stub, and places them upon a table 8, which I prefer to form of the front door of a cabinet 17. The table 8 is provided with the letters of the alphabet suitably arranged. As the orders are removed from the stubs, they are placed alphabetically according to the customers' names in the spaces under the corresponding letters on the table. Suitable spaces are also provided and marked "Paid" and "Void" (Figs. 2 and 3) upon which duplicates of paid orders and void orders respectively are placed. Then the duplicates marked paid are assorted alphabetically, the amounts added, and the resulting amount checked with the cash in the cash drawer, after which they are added to the bottom of the pile of charged duplicates. The voided duplicates may be added also finally, if desired. By this means they may be quickly assorted alphabetically.

When the order duplicates have been assorted the different piles are placed upon each other successively, beginning with A, and thus all the duplicates are assembled into a book 12, arranged alphabetically by customers' names. A perforation 9 is provided in the duplicates through which is now placed a paper fastener 10. A tab 11, having a suspending ring, may now be stuck to the back of book 12 and fastened by means of fastener 10. The order duplicates are then numbered consecutively by writing upon each a page number, as shown at 13. If a bookkeeper is employed the proprietor may at any time check the bookkeeper's work if he himself makes up the books of

order duplicates at the end of the day and writes the page number 13 thereon in his own handwriting, so that any attempt to erase these numbers and rewrite them may be detected. In this way the proprietor may easily prevent collusion between the bookkeeper and the salesmen and may trace responsibility for errors made by either. The day's business is now ready for posting in the ledger 15 (Fig. 10). As each order duplicate is posted, the number of the page of the ledger upon which the account is posted is written under the number of the order duplicate as shown at 14 (Fig. 5). In the ledger, the day of the month, the page of the book of duplicates, and the amount of the purchase is posted. The names of customers are arranged in the ledger alphabetically, which greatly facilitates posting, because the ledger index is not required for posting. The ledger index 16 (Fig. 9) is of the usual form.

The cabinet 17 is provided, with a front door 8, which is let down and used as a table, as previously described. The cabinet is shown as provided with inner doors 18 and 19. On the outside of doors 18 and 19 are placed receptacles 20, preferably in the form of hooks, for the purpose of suspending books 12. Numbers corresponding to the days of the month are placed on doors 18 and 19 at the hooks, and the book 12 formed from each day's business is suspended on its corresponding hook.

When all the hooks 20 upon both doors are occupied with books, which is after the first of the succeeding month, they may be removed and placed in order in one of the compartment receptacles 21, provided within cabinet 17 (Fig. 4). In order to keep the books separate from one another and facilitate the removal of any one desired, I prefer to place a tab-card 22 under each book and mark the portion of the card which projects beyond the book with the date of the book. Thus any book of duplicates required may be readily withdrawn and replaced after use.

Having thus described my invention so that any one skilled in the art pertaining thereto may make and use it, I claim—

A filing cabinet comprising a body portion divided into a plurality of compartments, a pair of horizontally swinging doors hinged to said body portion and adapted to completely close the front thereof, a vertically swinging door hinged to the lower edge of said body portion, said door forming a table when in its lowered position, and overlying the inner doors when in its closed position, and a plurality of book-receiving hooks carried by said inner doors, the upper face of the vertically swinging door bearing letters of the alphabet.

CHARLEY GRANT WARD.
